(57) **CLAIM**

The ornamental design for a corner bracket, as shown and described.

DESCRIPTION

FIG. 1 is a perspective view of a corner bracket;

FIG. 2 is another perspective view thereof;

FIG. 3 is a front view thereof;

FIG. 4 is a back view thereof;

FIG. 5 is a right side view thereof;

FIG. 6 is a left side view thereof;

FIG. 7 is a top view thereof;

FIG. 8 is a bottom view thereof; and,

FIG. 9 is another perspective view shown thereof in a position of use.

The broken lines shown in FIG. 9 depict environmental subject matter that forms no part of the claimed design.
